SEAR DEVICE FOR AN AUTOMATIC FIREARM

Edward C. Lee, Detroit, Mich., assignor to the United States of America as represented by the Secretary of the Army

Application December 23, 1953, Serial No. 400,150

6 Claims. (Cl. 89—136)

This invention relates to automatic firearms wherein a firing member is resiliently mounted for slideable movement in a reciprocating bolt and is particularly directed to means for securing the firing member in a cocked position and for the release thereof when the bolt is in a battery position.

In automatic firearms of the type described in Patent No. 1,628,226 to John M. Browning, there is provided a longitudinally reciprocating bolt having a spring-biased firing member mounted for slideable movement between a forward firing position and a rearward cocked position. The firing member is arranged to be releasably retained in the cocked position by a spring-biased sear reciprocably mounted in vertical slideways. When the bolt is moved to the battery position, the sear is actuated by suitable means to release the firing member which moves forwardly under the bias of its spring to discharge the chambered cartridge. During the ensuing recoil movement of the bolt, a cocking lever pivotally mounted therein, moves the firing member rearwardly ready for engagement with the sear. During counter-recoil of the bolt, the cocking lever is counter-rotated permitting the firing member to be biased slightly forward into releasable engagement with the sear and the bottom end of such cocking lever is swung free of the firing member whereupon the latter is free to move forwardly when released by the sear to effect another cycle of operation.

In firing mechanisms of this type, considerable trouble has been experienced with the sear prematurely releasing the firing member whereby the chambered cartridge is not fired because the firing member does not strike the primer with sufficient force to ignite it. Further, by the sear being biased to the firing member engaging position by a spring, which must necessarily exert considerable force thereagainst to maintain positive engagement with the firing member, an undesirably large solenoid has to be provided to actuate the sear when the firearm is to be operated by electrical means. Moreover, by the conventional sear being mounted in slideways, little bearing surface is provided and therefore considerable frictional strain opposes movement of the sear.

Accordingly, it is an object of this invention to provide in an automatic firearm bolt a sear which holds the firing member in positive engagement until actuated by a trigger mechanism.

A further object of this invention is to provide in an automatic firearm bolt a pivotally mounted sear which reciprocates smoothly between a firing member holding position and a disengaging position.

It is a specific object of this invention to provide in an automatic firearm bolt a pivotally mounted sear which operates without springs and which positively holds the sear in engagement with the firing member until actuated by a trigger mechanism.

The specific nature of the invention as well as other objects and advantages will clearly appear from a description of a preferred embodiment as shown in the accompanying drawings in which:

2

Fig. 1 is a longitudinal cross-sectional view of a firearm receiver showing the bolt in non-fire battery position and the firing member held in cocked position by the sear;

Fig. 2 is a view taken along line 2—2 of Fig. 1;

Fig. 3 is an enlarged exploded view showing the mating ends of the trigger bar and the operating solenoid;

Fig. 4 is an enlarged fragmentary view similar to Fig. 1 but showing the bolt in a partial recoil position;

Fig. 5 is a fragmentary view similar to Fig. 3 but showing the bolt in battery position and the sear in firing member disengaging position;

Fig. 6 is an end view of the bolt partially cross-sectioned to show the sear actuator engaged with the trigger bar in non-fire position;

Fig. 7 is an enlarged exploded view of the sear mechanism of this invention;

Fig. 8 is a fragmentary view partially cross-sectioned to show the relationship of the sear actuator lug with the trigger bar when in non-fire position during counter-recoil of the bolt; and

Fig. 9 is similar to Fig. 8 but showing the trigger bar in fire position.

Shown in the figures is a firearm of the well-known Browning type having a receiver 12, a bolt 13 slidably mounted therein for reciprocable movement between a firing and a retracting position, a top plate bracket 14 depending from the top side of such receiver, a trigger bar 15 pivotally mounted on one side of such top plate bracket and a solenoid 16 engaged to such trigger bar for actuation thereof. Solenoid 16 is so arranged that when charged the forward end of trigger bar 15, noted by 17, is rotated downwardly clockwise from a non-fire to a fire position and is returned by conventional spring means to non-fire position when the charging is stopped.

Provided in the side of trigger bar end 17 opposite top plate bracket 14 is a step portion 18 which extends below the bottom side of such end and provided in the inner side of the extending portion thereof is a longitudinal slot 19. A cam portion 20 leads from the bottom side of trigger bar 15 to slot 19. Provided longitudinally along the side of top plate bracket 14 adjacent trigger bar 15 is a bar 21 which will be further described hereinafter. The bottom side of slot 19 is arranged to be aligned with the top side of bar 21 when trigger bar 15 is in non-fire position.

Provided in bolt 13 is a longitudinal bore 23 and a counterbore 22 in which there is slidably mounted a firing member 24 reciprocable between a firing position and a retracting position. Firing member 24 is comprised of an extension 25 receivable by counterbore 22 and a striker 26 receivable by bore 23. Provided in extension 25 is a longitudinal hole 27, which receives a compressible spring 28, and a rearwardly adjoining vertical slot 29. The underside of the rear end of extension 25 is slotted, as noted by 30, and depending from the rear end thereof is a forwardly facing hook 31.

Provided in the top side of bolt 13 is a recess 32 from the bottom side of which a slot 33 and a hole 34, disposed forwardly thereof, extend downwardly to counterbore 22. A pin 35 is mounted in bolt 13 so as to traverse slot 33 and mounted thereon for rotational movement

80 a cocking lever 35. The end of cocking lever 35 extending below pin 35, noted by 36, is provided with an actuating surface 43 which is engageable with the rear end of slot 29. The upper end of cocking lever 32 is engageable with a V-slot 37 in top plate bracket 14 when bolt 13 is adjacent battery position whereby such cocking lever is rotated during recoil of bolt 13 to move firing member 24 from firing to retracting position during the first part of the recoil of such bolt. Firing member 24

65 is maintained in retracting position during the remainder of the recoil of bolt 13 by engagement of a holding surface 64 on the lower end of cocking lever 35 and the

slidable engagement of the top end of cocking lever 35 with the bottom side of top plate bracket 14 as is best shown by Fig. 4. During counter-recoil of bolt 13 cocking lever 35 is counter-rotated by reengagement with V-slot 37, moving end 36 free of slot 29 to permit firing member 24 to be biased by spring 28 to cocked position.

Mounted in recess 32 is a member 38 comprised of a pin portion 39 and an arm portion 40. Pin portion 39 is receivable by hole 34 and extends downwardly therethrough to be slidably received by slot 29 and to engage the rear end of spring 28 whereby firing member 24 is biased from retracting to firing position. The front end of arm portion 40 is terminated by an upwardly arching arcuate portion 41, engageable by the top portion of cocking lever 35, and the rear end is arranged to be normally contiguous one side of slot 33.

Mounted laterally through bolt 13 is a pin 42 which traverses firing member 24 through slot 29 rearwardly of pin 39. Pin 42 traverses firing member 24 by means of elongated slots 45 which permit uninterrupted reciprocal movement of firing member 24. A sear 46 is mounted on pin 42 for pivotal movement between an upward holding position and a downward disengaging position. Sear 46 is comprised of an arm portion 47, which extends rearwardly and downwardly through slot 29, and a body portion 48 which extends vertically upward therefrom. Body portion 48 is received by an opening 58 in the rear end of bolt 13. In the front side of body portion 48 is a recess shown by 49, arranged to receive the rear end of firing member 24 and cocking lever end 36. A lateral indent 50 is provided in the bottom side of recess 49 to receive hook 31 when firing member 24 is in retracting position and sear 46 is in holding position. Formed by indent 50 is a rearwardly facing engaging surface 51, which cooperates with hook 31 for releasably holding firing member 24 in the cocked position which is slightly forward of the retracting position, and a land portion 44 arranged to be slidably engageable with hook 31 during reciprocation of firing member 24 between firing and cocked positions.

In the upper side of recess 49 there is provided a locking surface 59 which is engageable by actuating surface 43 of cocking lever 35. Locking surface 59 is so arranged that sear 46 is moved from disengaging to holding position by the engagement of actuating surface 43 therewith after firing member 24 has been moved thereby to retracting position during rotation of cocking lever 35. Extending downwardly from the top side of bolt 13 is a hole 52 which communicates with opening 58. Mounted for slidable movement in hole 52 is a cylindrical actuator 55. In the lower portion of actuator 55 there is provided a tongue portion 61 which is formed by a longitudinal groove 60 and the bottom end of the actuator. Groove 60 and tongue 61 are arranged to interlock with a tongue 62 and a groove 63 provided in the upper portion of body portion 48 and thereby separably joins actuator 55 and sear 46. Projecting outwardly from the top end of actuator 55 is a lug portion 56 which is adapted to be slidably receivable by slot 19 when sear 46 is in holding position and trigger bar 15 is in non-fire position. Lug 56 is movable along the bottom side of bar 21 during recoil of bolt 13 and is slidably engaged with the top side of such bar during counter-recoil. Further, lug 56 is arranged to be engageable with cam surface 20 when trigger bar 15 is in fire position whereby actuator 55 is deflectable downwardly to move sear 46 to disengaging position.

To fire the firearm in which the sear mechanism of this invention is embodied, solenoid 16 is charged whereby trigger bar 15 is pivoted from non-fire to fire position. It is to be noted that mechanical means may also be employed in actuating trigger bar 15. As has hereinbefore been described, when bolt 13 is in battery and trigger bar 15 is in non-fire position, lug 56 on actuator 55 is received by slot 19 in trigger bar end 17. There-

fore, when trigger bar 15 is depressed to fire position, sear 46 is actuated thereby to disengaging position, releasing firing member 24 which is biased forwardly by spring 28 to fire the chambered cartridge.

In the ensuing recoil of bolt 13, sear 46 is held in disengaging position by the engagement of hook 31 with land portion 44 and by the engagement of lug 56 with the underside of bar 21 as it moves therealong. During the initial portion of the recoil movement, the top end of cocking lever 35 engages with V-slot 37 and thereby rotates such cocking lever on pin 57. During the rotation of cocking lever 35, actuating surface 43 thereon engages the rear end of slot 29, actuating firing member 24 to retracting position, and finally engages with locking surface 59 to move sear 46 upwardly to holding position whereby hook 31 is received in indent 50, with the engagement of holding surface 64 with the rear end of slot 29 holding the firing member in the retracting position. The upward movement of sear 46 to holding position is arranged to take place after lug 56 has passed the rear end of bar 21. Sear 46 is maintained in holding position and firing member 24 in retracting position during the remainder of the recoil of bolt 13 by the engagement of the top of cocking lever 35 with the bottom side of top plate bracket 14.

In the following counter-recoil of bolt 13, lug 56 which was moved upwardly with sear 46 during the preceding recoil of the bolt moves along contiguous the top side of bar 21 so that when cocking lever 35 is counter-rotated by reengagement with V-slot 37, which moves actuating surface 43 thereon away from locking surface 59, sear 46 is secured in holding position by the slidable engagement of lug 56 with the top side of bar 21. Also, during the counter-rotation of cocking lever 35, firing member 24 is permitted to be biased slightly forward by spring 28, engaging surfaces 51 with hook 31 in the cocked position.

If it is desired to have automatic fire, trigger bar 15 is held in fire position by solenoid 16. Therefore, when bolt 13 moves into battery, lug 56 engages cam portion 20 of trigger bar 15 to move actuator 55 and consequently sear 46 to disengaging position, again releasing firing member 24 to fire the chambered cartridge.

If it is desired to cease fire, trigger bar 15 is permitted to return to non-fire position. Consequently, when bolt 13 moves into battery, lug 56, instead of engaging cam portion 20 to depress sear 46, is received by slot 19 in trigger bar 15 to engage sear 46 with trigger bar 15 and thereby the sear is held in holding position until the trigger bar is pivoted to fire position. Solenoid 16 is of a conventional adjustable type whereby the fire position of trigger bar 15 may be adjusted so that cam portion 20 actuates sear 46 when bolt 13 is the proper distance away from battery. Solenoid 16 is also arranged to normally bias trigger bar 15 to non-fire position, consequently sear 46 is, by the engagement through actuator 55 with trigger bar 15, held resiliently in holding position during non-fire by the spring-bias of such solenoid.

Although a particular embodiment of my invention has been described in detail herein, it is evident that many variations may be devised within the spirit and scope thereof and the following claims are intended to include such variations.

I claim:

1. In a firearm, a bolt reciprocable between a recoil and a battery position provided with a firing member spring-biased from a retracted to a firing position, a sear pivotally mounted in said bolt for releasably latching said firing member in said retracted position, means for actuating said sear comprising a cam, a lever for actuating said firing member to said retracted position and for subsequently lifting said sear into latching cooperation with said firing member during movement of said bolt to said recoil position, means for slidably holding said sear in said latching cooperation during move-

ment of said bolt to said battery position, a trigger bar mounted on the firearm for pivotal movement between a fire and a non-fire position, means for actuating said trigger bar to said fire position and for resiliently biasing said trigger bar to said non-fire position, interlocking means for releasably joining said sear to said trigger bar when said bolt is adjacent said battery position and said trigger bar is in said non-fire position, whereby said sear is movably responsive to actuation of said trigger bar.

2. In a firearm, a top plate bracket provided with a V-slot, a bolt reciprocable between a battery and a recoil position, said bolt being provided with a slideable firing member normally biased from a retracted to a firing position, said firing member being provided with a vertical slot having an end wall, a sear provided with a downwardly facing locking surface, said sear being mounted in said bolt for pivotal movement between a firing member holding position and a disengaged position and being cooperable with said firing member for releasably latching thereof in a cock position forward of said retracted position, a cocking lever pivotally mounted in said bolt to form an upper portion and a lower portion, said upper portion being cooperable with said V-slot during reciprocation of said bolt for actuation of said cocking lever, an actuating surface on said lower portion, said actuating surface being engageable with said end wall for moving said firing member to said retracted position and subsequently with said locking surface for pivoting said sear to said holding position during movement of said bolt to said recoil position and a holding surface on said lower portion engageable with said end wall for holding said firing pin to said retractor position until said cocking lever is pivoted by said bolt during movement thereof to said battery position.

3. In a firearm, a top plate bracket provided with a V-slot, a trigger bar pivotable between a fire and a non-fire position, actuating means cooperable with said trigger bar for actuation of said trigger bar to said fire position and for normally biasing said trigger bar to said non-fire position, a longitudinal slot in the front end of said trigger bar, a cam surface on the underside of said trigger bar, a bolt reciprocable between a battery and a recoil position provided with a slideable firing member normally biased from a retracted to a firing position, said firing member being provided with a vertical slot having an end wall, a longitudinal bar fixedly mounted to said top plate bracket parallel with the travel of said bolt, said longitudinal slot being alignable with the top side of said longitudinal bar when said trigger bar is in said firing position and with the bottom side of said bar when in said non-fire position, a sear provided with a recess having an upper locking surface for receiving the rear end of said firing member, said sear being mounted in said bolt for pivotal movement between a firing member holding position and a disengaged position, an engaging surface in the bottom side of said recess cooperable with a hook on the rear end of said firing member for releasably latching said firing member in a cocked position forward of said retracted position, a cocking lever pivotally mounted to said bolt to form an upper portion and a lower portion, said upper portion being cooperable with said V-slot for actuation of said firing member during reciprocation of said bolt, an actuating surface on said lower portion cooperable with said end wall for moving said firing member to said retracted position and subsequently with said locking surface for pivoting said sear to said holding position during movement of said bolt to said recoil position and for release of said firing member into engagement with said sear in said cocked position during movement of said bolt to said battery position, an actuator member interlocked with said sear for movement together, a lug protruding from said actuator member for sliding engage-

ment with the bottom side of said longitudinal bar to hold said sear in said disengaged position during movement of said bolt to recoil position and said firing member to said retracted position and for sliding engagement with the top side of said bar after said sear is actuated by said cocking lever to said firing member holding position whereby said sear is maintained in said holding position until said bolt is in said battery position, said lug being deliverable from the top side of said longitudinal bar into engagement with said cam surface when said trigger bar is in said fire position for automatically pivoting said sear to said disengaging position or into said longitudinal slot for securing said sear in said holding position when said trigger bar is in said non-fire position.

15 4. In a firearm, a bolt movable in recoil responsive to actuation of the firearm, said bolt being provided with a firing member spring-biased from a retracted to a firing position, a pivotal sear for releasably latching said firing member in said retracted position and a cocking lever pivoted during recoil movement of said bolt into engagement with said firing member for actuation thereof to said retracted position and into subsequent engagement with said sear for pivotal actuation thereof into position to releasably latch said firing member in said retracted position.

20 5. In a firearm provided with a V-slot, a bolt reciprocable between a recoil and a battery position, said bolt being provided with a firing member spring-biased from a retracted to a firing position, a sear pivotable to a position for releasably holding said firing member in said retracted position and a cocking lever pivotally mounted on a transverse pin to form an upper end engageable by the V-slot for pivoting said cocking lever during the reciprocation of said bolt and a lower portion reciprocable in a slot having an end wall provided in said firing member, an actuating portion on said lower portion cooperable with said end wall for actuating said firing member to said retracted position during pivotal movement imparted to said cocking lever during movement of said bolt to said recoil position, a recess in said sear for receiving said lower portion, a surface on the top side of said recess engageable by said actuating portion after said firing member is moved thereby to said retracted position for moving said sear into position to hold said firing member in said retracted position, an actuator member interlocked at the bottom end thereof to said sear for joint movement together, and a lug portion extending from said actuator to slidably engage the top side of a bar mounted on the firearm longitudinal to the movement of said bolt for holding said sear in holding engagement with said firing member during movement of said bolt to said battery position.

25 6. In a firearm, a reciprocating bolt provided with a firing member spring-biased from a retractor position to a firing position, a sear pivotally mounted in said bolt for releasably latching said firing member in said retractor position, a pivotal cocking lever for actuating said firing member to said retractor position and for subsequently pivoting said sear into engageable cooperation with said firing member responsive to recoil of said bolt, a longitudinal bar mounted on the firearm parallel with the reciprocating travel of said bolt, and means for connecting said sear with said bar during counter-recoil of said bolt whereby said sear is slidably maintained in holding engagement with said firing member.
